DESIGN FOR A DRESS

Abraham M. Katz, Freeport, N. Y.

Application July 12, 1945, Serial No. 120,653

Term of patent 3½ years

(Cl. D3—26)

To all whom it may concern:

Be it known that I, Abraham M. Katz, a citizen of the United States and a resident of the Town of Freeport, in the county of Nassau and State of New York, have invented a new, original, and ornamental Design for a Dress, of which the following is a specification, reference being had to the accompanying drawing forming a part thereof.

Fig. 1 is a front view of a dress showing my design.

Fig. 2 is a rear view thereof.

I claim:

The ornamental design for a dress, substantially as shown.

ABRAHAM M. KATZ.
